UNITED STATES PATENT OFFICE.

EDWIN STANLEY ROBBINS, OF WATERBURY, CONNECTICUT.

DESIGN FOR A HANGER FOR ARTICLES OF MERCHANDISE.

SPECIFICATION forming part of Design No. 27,923, dated November 30, 1897.

Application filed July 20, 1897. Serial No. 645,265. Term of patent 7 years.

To all whom it may concern:

Be it known that I, EDWIN STANLEY ROBBINS, of the city of Waterbury, New Haven county, Connecticut, have invented and produced a new and original Design for a Device for a Hanger for Articles of Merchandise, of which the following is a specification, reference being had to the accompanying drawing, forming a part thereof.

10 My purpose in producing the article the design of which is illustrated in the drawing has been to provide a novel and attractive and at the same time convenient, compact, and cheap means for use in displaying articles for advertisement or sale in stores and other places or for use in the home or office for the attachment thereto of the various articles needed for frequent needs.

15 The drawing represents my design for a hanger for articles of merchandise in perspective.

20 A is the body part, consisting of a band of any convenient metal or material formed into a circular or substantially circular shape.

25 I cut out of this band strips or portions for the purpose of ornamentation, which are shown in the drawing in the present instance to be what might be termed "link-shaped," and are represented by the letter a.

B B are chains fixed at one end to the band 30 portion at suitable intervals and brought together and connected to a device by which the whole may be suspended, represented in the drawing by the circular ring C.

To the band are connected individual hangers 35 for articles of merchandise, represented in the drawing by the pear-shaped or substantially triangular pieces D. These are connected to the band or body portion, as shown in the drawing, by rings a'. The 40 lower portion of the individual hanger for articles of merchandise is formed into eyelets d, by means of which the articles to be suspended from the hanger for articles of merchandise may be attached by hooks or 45 snaps or any other convenient means.

Having thus described my invention, I claim—

The design for a hanger for articles of merchandise substantially as herein shown and 50 described.

In testimony whereof I have signed this specification in the presence of two subscribing witnesses.

EDWIN STANLEY ROBBINS.
